UNITED STATES PATENT OFFICE.

MARTIN HETHERINGTON, OF SPRINGFIELD, MASSACHUSETTS, ASSIGNOR TO
J. W. STEERE & SON, OF SAME PLACE.

ORGAN.

SPECIFICATION forming part of Letters Patent No. 542,221, dated July 2, 1895.

Application filed October 13, 1894. Serial No. 525,803. (No model.)

To all whom it may concern:

Be it known that I, MARTIN HETHERINGTON, a subject of the Queen of Great Britain, residing at Springfield, in the county of Hampden and State of Massachusetts, have invented new and useful Improvements in Organs, of which the following is a specification.

This invention relates to what is known as "tubular pneumatic valve-operating mechanism" for pipe-organs.

The objects of the invention are to devise "pneumatics" or pneumatic motors which shall be of improved construction and operative capability, and also to devise valve-operating devices which shall be of greater sensitiveness and capable of quicker repetition when operated by a very distant pedal or key than any tubular pneumatic apparatus heretofore known to me.

To these ends the invention consists in constructions and combinations of parts, all substantially as will hereinafter fully appear and be set forth in the claims.

Reference is to be had to the accompanying drawings, in which—

Figure 1 is a vertical sectional view through the wind-chest of a pipe-organ, showing the present improved pneumatic valve-operating mechanism operatively applied. Fig. 2 is a perspective view of one of the adjustable valve-seats.

In the drawings, A represents the wind-chest for feeding a series of pipes, one of which is indicated by the dotted lines at α . From the bottom of the wind-chest the passages lead to the respective pipes, one of these being indicated at a . The passages are formed in a rail or board B, which is set under the wind-chest, each passage extending downwardly from the bottom interior of the wind-chest, it being then horizontally continued and then vertically directed to receive the lower end of the pipe.

b represents the valve for the one-pipe passage, it resting to close the orifice a^2 of the passage a , and this valve has the stem b^2 depending therefrom through a hole d in the bottom of the board or rail B, where it is provided with the secondary valve f , which normally remains open, but is adapted to close said hole when the valve b opens from the ori-

fice a^2 to sound the pipe. This arrangement of double valves is common. The said valve b depends from the movable bottom board g^3 of the individually-applied pneumatic g . This pneumatic comprises the top board g^2 , which is glued or otherwise immovably secured to the top of the wind-chest, the flexible and collapsible sides g^4 , and the aforementioned bottom g^3 , movably supported by said flexible sides. The said pneumatic has one or more small openings h leading thereinto for communication with the wind-chest.

On top of the wind-chest are two rails or wooden strips C D, the one, C, being directly over the row of the pneumatics g , while the other, D, is opposite and separated from the one, C, by a short distance, as seen. A passage j is bored or formed through the top of each pneumatic, the top of the wind-chest, and upwardly into the rail C, while a branch hole j^2 is horizontally and transversely formed to extend from the side of the rail C, which is toward the rail D, to intersect each vertical passage j . A short length of externally-screw-threaded brass tubing k is screwed into the hole j^2 and projects therefrom, so that its end stands about at the sidewise-opening orifice of the individual hole or chamber i in the side of rail D.

The tube n communicates with each of the chambers, it extending therefrom to the distant pedal or key, which is sometimes as far as eighty feet or more away from the wind-chest. The pedal or key-operated valve o normally closes the proximate end of the said tube n , while the orifice i^2 of the said chamber i is covered by the imperforate and marginally-secured disk or diaphragm t , of sheep-skin or the like, which, not being taut, is subject to the slightest variations of air-pressure at either side, whereby it may have a vibration either to lie against and close the end of the transverse nozzle or tube k , or be withdrawn inwardly from such closing relation to open such tube, which places the interior of the pneumatic g in communication with the atmospheric air.

Each of the tubes k has on its end the washer k^2 , of sheep-skin, permanently secured thereon by a suitable cement, and constituting internal and external projecting flexible flanges

to form a more efficient seat for the transversely-deflecting diaphragm.

There is a minute passage *m* leading from the common wind trunk or chest *A* to each of the individual chambers. It will be understood that all of the valves, passages, and pneumatic devices described are reduplicated in the organ system, no part being in common except the wind-chest *A*.

- 10 Now the operation of the apparatus is as follows: There is the usual bellows-pressure in the wind-chest, and valve *o* is assumed to be closed. There is therefore a uniform pressure in the wind-chest inside of the pneumatic 15 *g* and in the passage *j* and tube *k*, as well, also, as in the chamber *i*, and the gravity of the bottom board of the pneumatic, assisted, if desired, by the weight *g*⁵, causes the pneumatic to sag to its lowest distension, leaving 20 the valve *b* on its seat, closing the passage *a*. The flexible diaphragm, under these conditions, will always be in closing relation to the end of the tube *k*. Now when the valve *o* is opened by the pedal or key the pressure in 25 chamber *i* is exhausted or relieved synchronously, the diaphragm drawing inwardly from the end of tube, whereupon the pneumatic *g* is in free communication with the atmospheric air and the bellows-pressure in the wind- 30 chest *A* collapses the pneumatic with the very peculiar result of lifting its bottom board *g*³, and with it the valve *b*, opening the pipe-passage *a* to the wind-chest pressure. Now, when the valve *o* is closed, the pressure in 35 chamber *i* is immediately re-established, the diaphragm instantaneously closing against the end of the tube, and the pneumatic *g*, in consequence of, although simultaneously with, such closing of tube *k*, becomes dis- 40 tended, and the valve *b*, supported thereby, descends to its seat. The repetitions and re- 45 sponse of the tubular pneumatic-valve devices following the opening and closing of the pedal or key-valves *o* is in practice as rapid, sharp, and distinct as the manipulation of the fingers of the organist.

The pressure admitted from the wind through the passage *a* may of course be utilized for any of the other well-known purposes 50 common in tubular pneumatic organs than directly sounding the pipes.

Having thus described my invention, what I claim, and desire to secure by Letters Patent, is—

- 55 1. In an organ, a wind-chest with a passage leading therefrom having a valve thereat, a collapsible pneumatic, having a movable wall by which the said valve is supported, and having a small opening communicating from the 60 wind-chest to its interior, a passage leading from the interior of said pneumatic to the exterior of the wind-chest, a chamber having an opening opposite the orifice of said passage from the pneumatic, having a passage leading 65 thereinto from the wind-chest, and having a flexible deflecting diaphragm covering said opening which is adapted to close the end of

70 said passage from the pneumatic, and a tube leading from the said chamber and having a normally closed valve, substantially as described.

75 2. In an organ, a pipe, a wind-chest with a passage, *a*, leading from its bottom to the pipe, having a valve, *b*, thereat, a collapsible pneumatic depending from the top wall of the wind-chest having a movable bottom to which the said valve is connected and having a small opening communicating from the wind-chest to its interior, a passage leading from the interior of said pneumatic to the exterior of the 80 wind-chest, a chamber having an opening opposite the orifice of said passage from the pneumatic, having a passage leading thereinto from the wind-chest, and having a flexible deflecting diaphragm covering said open- 85 ing which is adapted to close the end of said passage from the pneumatic, a tube leading from the said chamber and having a pedal or key-operated valve, substantially as described.

90 3. In an organ, the wind-chest, *A*, having the outlet passage leading from its bottom to the sound producing device, and having a pneumatic suspended therewith which comprises an inclosed chamber with a movable bottom and flexible collapsible sides supporting said bottom, which latter is directly over the said outlet passage, and constructed with a valved passage leading from its interior to atmospheric air, and with a small unvalved 95 passage communicating from its interior to said wind-chest, a valve supported by said movable bottom of the pneumatic which normally closes said outlet passage, a key, or like part, and means actuated by, and intervening between the key and said valved passage which leads from the interior of the pneumatic, substantially as and for the purposes set forth.

100 4. In an organ, a pneumatic, or motor, with a passage leading therefrom having a nozzle-like terminus, a chamber with an opening opposite such nozzle having a flexible, marginally secured, and laterally deflecting diaphragm covering it, and adapted to lie against and close the nozzle end of said passage, in 105 combination with apparatus for maintaining a uniform pressure in both the pneumatic and said chamber, and a pipe leading from said chamber having a valve which, opened, exhausts said chamber and effects the drawing of said diaphragm away from said passage nozzle, substantially as described.

110 5. The combination with the wind-chest having the rail, or board, *C*, at its top, with a pneumatic, *g*, suspended from its upper wall 115 and with the passage, *j*, leading from the interior of said pneumatic up through the top of the wind-chest and within said board, a section of tube, *k*, entering said board, *C*, to connect with said passage, *j*, the chamber, *i*, with the diaphragm-closed opening adjacent the end of said tube and means for maintaining and exhausting the pressure from said chamber, substantially as described.

6. In an organ, the combination with an exhaust passage for a wind chamber, or pneumatic, which consists of an open-end tube or nozzle with a washer of sheepskin, or a like flexible material secured on the end of said tube to constitute internal and external flexible flanges, of a chamber having an opening opposite said nozzle which is closed by a marginally connected diaphragm, and means for maintaining and exhausting at will the pressure in said chamber, substantially as described.

7. In an organ apparatus of the character

described, the combination with the rail, or board, D, having the chamber, i, with an orifice, and a deflecting marginally connected diaphragm closing said orifice, of the rail, or board, C, having the passage, j, the tube-section, k, screwing into an opening which connects with said passage, whereby said tube is adjustable toward and from the diaphragm, substantially as described.
